UNITED STATES PATENT OFFICE.

LINCOLN A. WELLS, OF HUNTLEY, MONTANA.

SHIP-FORM.

1,323,135.

Specification of Letters Patent. Patented Nov. 25, 1919.

Application filed September 27, 1918. Serial No. 255,918.

To all whom it may concern:

Be it known that I, LINCOLN A. WELLS, a citizen of the United States, residing at Huntley, in the county of Yellowstone and

5 State of Montana, have invented new and useful Improvements in Ship-Forms, of which the following is a specification.

This invention relates to ship forms, the object in view being to provide an apparatus 10 for forming the hulls of marine vessels of every description from concrete, at the same time incorporating reinforcing metal in the concrete hull during the formation thereof.

The chief object of the present invention 15 is to produce simple and reliable apparatus for adjusting and collapsing the forms, molds, or templets, irrespective of the size of the hull to be constructed, the different parts of the apparatus being mounted for 20 easy movement to and from their places thereby greatly expediting the construction of concrete vessels.

Another object of the invention is to provide novel means for supporting the reinforcing material incorporated in the hull.

Another feature of the invention resides in the particular means for supporting and holding the inner and outer sections of the mold or form in fixed relation to each other 30 during the process of pouring the concrete or other plastic material of which the hull is formed.

With the above and other objects in view, the invention consists in the construction, 35 combination and arrangement of parts, as herein described, illustrated and claimed.

In the accompanying drawings:

Figure 1 is a plan view of the ship form, showing also the dry dock in which the 40 molding apparatus is located, the inner form being omitted.

Fig. 2 is a plan view of the inner form removed.

Fig. 3 is a vertical longitudinal section 45 through the apparatus.

Fig. 4 is a vertical transverse section through the same.

Fig. 5 is an enlarged fragmentary vertical 50 transverse section showing the connection between the inside form and the launching base.

Fig. 6 is a detail perspective view of one of the eyes or cringles.

Fig. 7 is a detail perspective view of one 55 of the plugs.

Fig. 8 is a detail perspective view of one of the clamps.

Fig. 9 is a detail view showing the way of mounting and supporting the stages.

Fig. 10 is a fragmentary elevation of the 60 reinforcing structure.

Fig. 11 is a fragmentary section showing the hinged connection between the side walls and bottom section of the mold.

Referring to the drawings, 1 designates 65 the launching base of the ship molding form, said base, in the preferred embodiment thereof, comprising a foundation of concrete as indicated in the drawings, superimposed upon which is a base member 2, preferably 70 of wood, although any suitable material may be used therefor, the upper portion 2 of the launching base having its upper surface 3 shaped to conform to the bottom of the hull of the improved vessel to be produced, 4 75 designating the concrete hull of the vessel after completion. The launching base is formed at suitable points with sockets or steps 5, the purpose of which will presently appear.

Extending around the launching base is a concrete floor 6 and supported thereon are rails 7 which extend parallel to each other and transversely of the longitudinal axis of the launching base as shown in Fig. 1. 85

Mounted for rolling movement upon the rails 7, at opposite sides of the launching base are stages 8 shown as comprising base members 9 having flanged rollers or wheels 10 on the bottom thereof which rest and roll 90 upon the rails 7. The stages also comprise

standards 11 and braces 12 which serve to support an overhead platform 13 upon which is mounted any necessary number of concrete mixers 14, the spouts 15 of which are 95 arranged to discharge the concrete or other plastic material into the top or complete form or mold as indicated in Fig. 4. Each of the stages carries one of the outside mold

boards 16 of the ship form, such outside 100 mold board corresponding in shape with the shape of the outside of the hull of the vessel and having at its lower edge a butt joint relation at 17 with the adjacent edge of the upper portion 2 of the launching base 105

1. The outside mold board 16 may be formed of planks or boards which are shown as running horizontally although they may run in any direction. In case a very large

hull is to be formed, the outside mold boards 110

16 may be formed in any desired number of sections as indicated in the drawings, the sections being of such size that they may be readily moved toward and away from each other on the rails 7.

The inside form comprises a bottom section 18 having the general shape of the vessel and having secured thereto and projecting downwardly therefrom, a number of 10 supporting studs or pins 19, the lower ends of which are designed to rest in the steps or sockets 5 above referred to. The inside form also comprises side wall portions or sections 20 which may be divided into any 15 number of sections as indicated in Fig. 2, the side walls 20 embodying bow and stern sections 21 and 22 respectively which are connected by hinges 23 to the bottom section 18, the side sections 20 being also connected 20 to the bottom section 18 by means of hinges 24. The bottom surface of the bottom section 18 conforms to the shape of the upper surface of the bottom of the hull and the side wall sections 20 and 21 likewise 25 connect to the interior contour of the hull. In order to collapse the inside form shown in Fig. 2, the several sections of the side walls thereof are connected by cables 25 or the like to a shaft 26 extending longitudinally 30 of and within the inside form, suitable operating means 27 being provided for rotating the shaft 26. The bow and stern sections 21 and 22 are first drawn inwardly and thereafter the sections 20 are moved inwardly. Then the entire inside form is 35 raised as indicated in Fig. 3 by means of raising and lowering cables 28 connected to power at 29. The cables 28 pass over overhead sheaves 30 supported by an overhead 40 thrown beam 31, or the equivalent thereof, said beam being in turn supported by a suitable frame work 32, such as posts or standards.

I prefer to use the apparatus within a dry dock, the walls of which are indicated at 33 and in such case, the supporting frame work or posts 32 may rise from such dry dock walls.

The means for shifting the outside form 50 sections toward and away from each other is illustrated in Figs. 1 and 4, wherein it will be seen that I employ a number of rotatable feed screws 34 which have a threaded engagement with the adjacent 55 stage, each feed screw 34 being actuated by worm gearing 35, adjacent to the outer end thereof and a vertical shaft 36 to which motion is imparted by a suitable power shaft 37 surmounting the dry dock walls 33, the 60 shafts 36 and 37 being operatively connected together by gears 38. When the inside and outside sections of the form are in their proper final positions, the bottom portions of the outside sections 16 are secured 65 to the launching base by means of hinge

clamping members 39, each embodying a threaded clamping screw 40 as shown in Fig. 8, the clamping members 39 being preferably hinged to the outside form sections as shown at 41. Similar clamps 42 are employed for fastening the bottom edges of the mold board 16 to the corresponding edges of the launching base. In this way, the inside and outside forms are held in fixed relation to each other, during the period of time in which the plastic material is discharged from the mixers 14 between the sections of the mold or form. The dry dock is formed with a gate 43 in order that when the vessel is complete, the gate may be 70 opened and water admitted into the dry dock so as to float the vessel from off the launching base. 75

In order to properly position the inside and outside sections of the mold in relation to each other by means of the supporting studs or pins 19, eyes or cringles 44 are placed around said studs and between the mold boards of the inner and outer forms as shown in Fig. 5. Each of said eyes is 80 formed with a concaved periphery 45 so that it may be held by the concrete when poured between the outer and inner mold boards and each eye 44 is internally threaded as shown to receive a threaded 85 plug 46. After the concrete has been poured and has sufficiently dried, the inner section of the form is elevated by the raising and lowering means above described, and then a plug 46 is inserted in each eye or cringle 90 44, making the hull of the vessel water tight. 95

In the formation of the concrete hull, a reinforcing structure is incorporated therein, such reinforcing structure being illustrated in Fig. 10, and being preferably attached to the inside form while the latter is elevated as shown in Fig. 3. The reinforcing structure comprises, in one of the preferred embodiments thereof, horizontal members 47, such as rods or wires, the upper member 47 being formed with depressed offsets 48 to receive the hooked upper extremities 49 of inclined and crossed reinforcing members 50 also formed of rods or wires, the members 50 are arranged in two 110 parallel series crossing each other, as shown in Fig. 10, and cross portions thereof are fastened to the lower horizontal member or members 47 by means of tie wires 51 or the equivalent thereof. The horizontal members 115 are supported by means of hangers 52 each having the general shape of the letter W, the central portion thereof being formed with an inner offset 53 to receive the respective horizontal member and also one 120 of the inclined or cross members 50 as shown in Fig. 10. Each of the hangers 52 has terminal base portions 53 and bobs or spurs 54 at the extremities thereof which are 125 driven into the mold board to which the 130

reinforcing structure is attached preparatory to forming the concrete or other plastic material into the mold. Any desired number of hangers may be employed as 5 may be found necessary or expedient. The horizontal members 47 are connected to the hangers by tie wires 55.

The apparatus hereinabove described may be made of any size according to the size 10 and character of the vessel hull to be formed. Any and all kinds of marine hulls may be formed or manufactured by means of the apparatus herein described and shown. The hulls may be formed with much greater 15 rapidity than under the present practice of building a form for each hull and then taking such form to pieces in order to liberate the hull after the concrete is formed and allowed to dry. The inner and outer 20 forms or molds may be made in any desired number of sections which number will, of course, vary in accordance with the size of the hull. Complete hulls may be turned out with great rapidity thus particularly 25 adapting the apparatus for use in times of war to replace sunken vessels. The decks, propellers and other fittings required may be placed in proper position before the concrete is formed. When the hull is complete, 30 water is permitted to enter the dry dock, whereupon the vessel is floated and launched from the launching base. The water is then forced from the dry dock and the sections of the mold are again placed 35 in position preparatory to the formation of another hull.

I claim:—

1. In a ship form, the combination of a launching base, the upper surface of which 40 conforms to the shape of the bottom of a marine vessel's hull and forms a supporting saddle for said hull, stages at opposite sides of said launching base movable toward and away from the same, outside mold boards 45 carried by said stages, an inside form comprising a bottom section the lower surface of which conforms to the inner surface of the hull's bottom, and side wall sections hinged to said bottom section, and raising 50 and lowering means for said inside form.

2. In a ship form, the combination of a launching base, the upper surface of which conforms to the shape of the bottom, of a marine vessel's hull and forms a supporting 55 saddle for said hull, stages at opposite sides of said launching base movable toward and away from the same, outside mold boards carried by said stages, an inside form comprising a bottom section the lower surface 60 of which conforms to the inner surface of the hull's bottom, and side wall sections hinged to said bottom section, and raising and lowering means for said inside form.

3. In a ship form, the combination of a 65 launching base, the upper surface of which

conforms to the shape of the bottom of a marine vessel's hull and forms a supporting saddle for said hull, stages at opposite sides of said launching base movable toward and away from the same, outside mold 70 boards carried by said stages, an inside form comprising a bottom section the lower surface of which conforms to the inner surface of the hull's bottom, and side wall sections hinged to said bottom section, said 75 side walls being composed of a plurality of independently hinged sections, and raising and lowering means for said inside form.

4. In a ship form, the combination of a 80 launching base, the upper surface of which conforms to the shape of the bottom of a marine vessel's hull and forms a supporting saddle for said hull, stages at opposite sides of said launching base movable toward and 85 away from the same, outside mold boards carried by said stages, an inside form comprising a bottom section the lower surface of which conforms to the inner surface of the hull's bottom, and side wall sections 90 hinged to said bottom section, means within and carried by said inside form for collapsing said side wall sections inwardly, and raising and lowering means for said inside form. 95

5. In a ship form, the combination of a launching base, the upper surface of which conforms to the shape of the bottom of a marine vessel's hull and forms a supporting saddle for said hull, stages at opposite sides 100 of said launching base movable toward and away from the same, outside mold boards carried by said stages, an inside form comprising a bottom section the lower surface of which conforms to the inner surface of the hull's bottom, and side wall sections 105 hinged to said bottom section, raising and lowering means for said inside form, and clamping means for holding said inside form fixed in relation to the launching base and 110 the outside mold boards.

6. In a ship form, the combination of a launching base, the upper surface of which conforms to the shape of the bottom of a marine vessel's hull, and forms a supporting 115 saddle for said hull, stages at opposite sides of said launching base movable toward and away from the same, outside mold boards carried by said stages, an inside form comprising a bottom section the lower surface 120 of which conforms to the inner surface of the hull's bottom, and side wall sections hinged to said bottom section, raising and lowering means for said inside form, and supporting studs projecting from the bottom section of said inside form, the launching base having steps to receive said studs. 125

7. In a ship form, the combination of a launching base, the upper surface of which conforms to the shape of the bottom of a 130

marine vessel's hull, and forms a supporting saddle for said hull, stages at opposite sides of said launching base movable toward and away from the same, outside mold boards carried by said stages an inside form comprising a bottom section the lower surface of which conforms to the inner surface of the hull's bottom, and side wall sections hinged to said bottom section, raising and lowering means for said inside form, supporting studs projecting from the bottom section of said inside form, the launching base having steps to receive said studs, stud receiving eyes between the launching base and bottom section of the inner form through which said studs pass.

8. In a ship form, the combination of a launching base, the upper surface of which conforms to the shape of the bottom of a marine vessel's hull and forms a supporting saddle for said hull, stages at opposite sides of said launching base movable toward and away from the same, outside mold boards carried by said stages, an inside form comprising a bottom section the lower surface of which conforms to the inner surface of

the hull's bottom, and side wall sections hinged to said bottom section, raising and lowering means for said inside form, supporting studs projecting from the bottom section of said inside form, the launching base having steps to receive said studs, stud receiving eyes between the launching base and bottom section of the inner form through which said studs pass, and plugs insertible in said eyes.

9. In a ship form, the combination of a launching base, the upper surface of which conforms to the shape of the bottom of a marine vessel's hull and forms a supporting saddle for said hull, stages at opposite sides of said launching base movable toward and away from the same, outside mold boards carried by said stages, an inside form comprising a bottom section, the lower surface of which conforms to the inner surface of the hull's bottom, and side wall sections hinged to said bottom section, raising and lowering means for said inside form.

In testimony whereof I affix my signature.

LINCOLN A. WELLS.
